UNITED STATES PATENT OFFICE

JAMES DUNLOP, OF CHICAGO, ILLINOIS, ASSIGNOR, BY MESNE ASSIGNMENTS, TO WESTINGHOUSE ELECTRIC ELEVATOR COMPANY, A CORPORATION OF ILLINOIS

CABLE EQUALIZER

Application filed December 7, 1928. Serial No. 324,554.

My invention relates to hoisting drums employed for operating a plurality of cables and it has special relation to means for equalizing the pull exerted by the hoisting drums upon the cables.

In modern elevator installations, it is usual to employ a car of such weight and designed to carry such loads that it is necessary to support the car structure upon a plurality of cables that pass over, and are driven by, a hoisting drum in the upper part of the elevator shaft. Ordinarily, the cables are disposed in suitable grooves of V-shape in the hoisting drum in order to insure sufficient traction to cause the drum to exert the desired pull upon the cables in operating the elevator.

It is well known, however, that the pull exerted upon the individual cables by the hoisting drum varies considerably from time to time by reason of the slipping of the cables on the drum, the stretching of the cables or other causes. When the pull upon the individual cables differs, the greater part of the load of the elevator may be carried by only a small number of the cables and thereby subject them to excessive strain and wear.

Therefore, it is an object of my invention to provide for equalizing the pull exerted by a hoisting drum upon a plurality of load-bearing cables in such manner that all cables will carry equal shares of the load.

A further object of my invention is to provide a means for equalizing the pull exerted by a hoisting drum on a plurality of cables that will permit the employment of hardened-steel cables and hardened-steel supporting members therefor and thereby insure a longer life for the cables as well as for the drum.

It is also an object of my invention to provide a hoisting apparatus that shall be simple and efficient in operation and adapted for ready and economical manufacture, installation and repair.

Other objects of the invention will, in part, be obvious and will, in part, appear hereinafter.

For an illustration of one of the various forms my invention may take, reference may

be had to the accompanying drawing, in which:

Figure 1 is a view, in end elevation, partly broken away, of an elevator-hoisting apparatus constructed in accordance with my invention; and

Fig. 2 is a view, in section, taken on the lines II-II of Fig. 1.

In the drawing, I have indicated a car C (only the main supporting beam of which is shown) as suitably suspended by a plurality of cables 1, 2, 3, 4, 5 and 6 which pass over a hoisting drum D and a positioning pulley P to a suitable counter-weight CW (only the supporting beam of which is shown). The hoisting drum is illustrated as mounted upon, and keyed to, an operating shaft 7 which may be driven by any suitable source of power, such as an electric motor (not shown).

In order that the pull exerted by the hoisting drum upon the cables may be equally distributed among them when the elevator car C is being operated, the cables are supported upon the drum by a plurality of traction-equalizing rings 8, 9, 10, 11, 12, 13, and 14 that are provided with cooperating angular faces which form grooves of V-shape in which the cables ride.

The equalizing rings 8, 9, 10, 11, 12, 13 and 14 are loosely mounted on the outer periphery or face of the drum in a recess or groove 15 that is formed by a pair of cooperating flange rings 16 and 17 in such manner as will permit lateral movement of the rings in the grooves. The flange ring 16 is shown as constituting an integral part of the drum D, while the cooperating flange ring 17 for retaining the equalizing rings in position and for limiting their lateral movement is shown as a separate ring that is secured to the drum by means of a plurality of stud bolts 18. This construction permits the ready removal of the rings for repairs or replacements.

In order to prevent the equalizing rings from moving circumferentially relative to the drum D, they are bolted to the flange rings 16 and 17 by a plurality of cross bolts 19. The transverse holes 20 in the equalizing rings through which the cross bolts 19 extend are made sufficiently large to permit the

rings to move freely laterally, while preventing them from moving substantially circumferentially relative to the drum.

While the equalizing rings may be constructed of any suitable material, I prefer to make them of hardened steel in order to permit the use of hardened-steel cables therewith, thereby insuring a construction having a long life.

10 For the purpose of insuring good tractive engagement between the cables and the equalizing rings and, at the same time, assist in adjusting the load on the cables under various conditions, each cable is attached to 15 the car C and to the counter-weight CW by a suitable resilient connecting means, such as compression springs 21 and 22.

Inasmuch as the equalizing rings 8, 9, 10, 11, 12, 13 and 14 are loosely mounted in the 20 groove 15 on the drum D and may move freely in a lateral direction therein, they will adjust themselves laterally in accordance with the pressures of the cables 1, 2, 3, 4, 5 and 6 in the grooves formed by the 25 angular cooperating faces of the equalizing rings.

For instance, if the cables 2, 3 and 6 slip on the drum or stretch slightly while the drum is rotating, the pull exerted by the 30 drum upon them will decrease, while the pull and, therefore, the load on the other cables 1, 4 and 5 will increase. As the load on the cables 1, 4 and 5 increases, they will pull themselves deeper into their grooves, thereby 35 spreading apart the equalizing rings 8 and 9 and 11, 12 and 13. The spreading apart of these rings deepens the grooves for the cables 1, 4 and 5, thus permitting them to operate on a smaller drum diameter and 40 lessening the pull exerted upon them by the drum. At the same time, the spreading apart of the rings 8 and 9 and 11, 12 and 13 causes the rings 9, 10 and 11, and 13 and 14, to move closer together, thereby causing the cables 45 2, 3 and 6 to ride in grooves of slightly larger drum diameter and thus increasing the pull exerted upon them by the drum. Therefore, as the drum continues to rotate, the equalizing rings will adjust themselves in such manner 50 that the cables 1, 4 and 5 will be relieved of their over-load and the cables 2, 3 and 6 will take an equal share of the burden, thus equalizing the pull exerted by the drum upon the individual cables.

55 Where no means is employed for equalizing the pull upon the cables, a greater part of the load may be carried by only one or two of the cables. Hence, traction between the cables and the hoisting drum will be limited 60 to only those of the cables supporting the greater part of the load while the drum will exert substantially no tractive pull on the remaining cables. Therefore, in such installations, it is usually necessary to employ an 65 idler sheave to obtain a double wrap of the

cables around the hoisting drum for the purpose of obtaining sufficient traction from the few taut cables to support and move the car. Inasmuch as my invention provides for equalizing the pull upon the cables and thereby insures good traction upon each of the cables, its use, in many instances, will obviate the necessity of employing a construction embodying an idler sheave.

70 While the illustrated example constitutes a particular embodiment of my invention, I do not limit myself strictly to the details shown, since, manifestly, the same may be varied considerably without departing from the spirit of the invention, as defined in the 75 appended claims.

I claim as my invention:

1. The combination with a hoisting drum for a plurality of load-bearing cables, of a plurality of rings mounted on the drum and 80 having cooperating faces disposed to constitute bearing grooves for the cables, said rings being movable laterally to permit the pressure of the cables on their faces to adjust them in such position as to equally distribute the 85 pull of the drum on the cables.

2. The combination with a hoisting drum for a plurality of load-bearing cables, of a plurality of rings mounted on the drum and 90 having cooperating angular faces disposed to constitute bearing grooves for the cables, said rings being movable laterally to permit the 95 pressure of the cables on their faces to adjust them in such position as to equally distribute the pull of the drum on the cables.

100 3. The combination with a hoisting drum for a plurality of load-bearing cables, of a plurality of rings mounted on the drum and having cooperating angular faces disposed to constitute bearing grooves for the cables, 105 said rings being movable laterally to permit the pressure of the cables on their faces to adjust them in such position as to equally distribute the pull of the drum on the cables, and means for limiting the lateral movement of 110 the rings.

115 4. The combination with a hoisting drum for a plurality of load-bearing cables, of a plurality of rings mounted on the drum and having cooperating angular faces disposed to constitute bearing grooves for the cables, said rings being movable laterally to permit the pressure of the cables on their faces to adjust them in such position as to equally distribute the 120 pull of the drum on the cables, and means for limiting the circumferential movement while permitting the lateral movement of the rings relative to the drum.

125 5. The combination with a hoisting drum for a plurality of load-bearing cables, of a plurality of rings mounted on the drum and having cooperating angular faces disposed to constitute bearing grooves for the cables, said rings being movable laterally to permit the pressure of the cables on their faces to adjust 130

them in such position as to equally distribute the pull of the drum on the cables, and a cooperating pair of flange rings secured to the drum for retaining the rings on the drum and for limiting their lateral movement.

5 6. The combination with a hoisting drum for a plurality of load-bearing cables, of a plurality of rings mounted on the drum and having cooperating angular faces disposed to 10 constitute bearing grooves for the cables, said rings being movable laterally to permit the pressure of the cables on their faces to adjust them to such positions as to equally distribute the pull of the drum on the cables, and means 15 secured to the flange rings for limiting the circumferential movement while permitting the lateral movement of the rings relative to the drum.

7. In a hoisting apparatus having a plurality 20 of load-bearing cables, a hoisting drum having a face provided with a recess, a plurality of rings mounted in said recess and having cooperating angular faces disposed to constitute bearing grooves for the cables, said 25 rings being movable laterally in said recess to permit the pressure of the cables on their faces to adjust them to such positions as to equally distribute the pull of the drum on the cables, and means for limiting the circumfer- 30 ential movement while permitting the lateral movement of the rings relative to the drum.

8. In a hoisting apparatus for an elevator car having a counterweight, a plurality of hoisting cables, resilient means for attaching 35 the cables to the car, resilient means for connecting the cables to the counter-weight, a hoisting drum for operating the cables, a plurality of equalizing rings mounted on the drum and having angular faces disposed to 40 constitute bearing grooves for the cables, said rings being movable laterally to permit pressure of the cables on their faces to adjust them to such positions as to equally distribute the pull of the drum on the cables, means for 45 limiting the lateral movement of the rings, and means for limiting the circumferential movement while permitting the lateral movement of the rings relative to the drum.

In testimony whereof, I have hereunto sub- 50 scribed my name this 28th day of November, 1928.

JAMES DUNLOP.
